UNITED STATES PATENT OFFICE.

CHARLES E. BARKER, OF SAN FRANCISCO, CALIFORNIA.

DRAWING BOARD.

Application filed June 21, 1926. Serial No. 117,496.

This invention relates to drawing boards, but it is to be understood that my invention may be used for other purposes such for example as a bulletin board, means being provided for holding the bulletin without employing thumb tacks.

An object of my invention is the provision of a supporting member such as a board and releasable means for holding a sheet of paper to the board.

Another object of my invention is the provision of means whereby a sheet of paper may be readily placed in its proper position relative to the edge of the board.

With the foregoing objects in view, together with such other objects and advantages as may subsequently appear, this invention resides in the construction and arrangement of parts hereinafter described and claimed, and illustrated in the accompanying drawings, in which:

Figure 1 is a perspective view showing a drawing board and a sheet of drawing paper fixed thereto by the apparatus of my invention.

Figure 2 is a bottom plan view of my improved drawing board shown in Figure 1, and

Figure 3 is an irregular section taken on the broken line 3—3 of Figure 2.

Referring to the drawings for more detailed description thereof, the numeral 5 indicates a drawing board provided with aligned apertures 6, through which pass threaded bolts 7 of smaller diameter than the apertures 6. The bolts 7 are provided with heads 8 adjacent the upper face of the board. Washers 9 encircle the bolts 7 and contact with the lower face of the board 5. Washers 10 also encircle the bolts 7 and contact with the washers 9. Members 12 also encircle the bolts 7 and are held in spaced relation from the washers 10 by means of coiled springs 15. Nuts 16 threadedly engage the bolts 7 and press the members 12 against the coiled springs 15.

It will be noted that the springs 15 and the nuts 16 constitute means for adjustably securing the members 12 to the bolts 7. The positions of the members 12 on the bolts 7 determine the leverage employed for tilting the bolts. The members 12 are L-shaped in section as shown in Figure 3, and comprise portions 12^a, each having an aperture therethrough to receive the ends of coiled springs

17, the other ends of which are secured to the board by means of staples 18.

The coiled springs 17 are under such tension that they pull the bolts 7 in such a direction that one side of each of the bolts 7 press against the board.

In order to lift the sides of the bolts 8 which press against the board, so that a sheet of paper 19 may be inserted between the heads 8 and the board, means are provided whereby the pulling forces of the coils 17 may be counteracted, and such means are herein shown as comprising wires 21 secured at 22 to those points of the members 12 which are opposite the points of the latter members to which the springs 17 are secured. The wires 21 may be integral, as shown in Figure 2, the loop being secured to a channel-shaped member 25.

The channel-shaped member 25 is provided with a transverse, elongated slot 26, through which passes into the board a screw 27, the head of which contacts with a washer 28 which is adjacent the bottom of the channel shaped member 25. The channel-shaped member 25 is transversely slidable relative to the screw 27, and normally lies in such position that the wires 21 are not under tension, so that the coils 17 exert a pull on the bolts 7 to hold the latter in such positions that the heads 8 thereof securely hold the sheet of paper 18 on the board.

When it is desired to release the pressure of the heads 8 from the sheet of paper, the channel-shaped member 25 may be pulled towards the edge 30 of the board, whereupon a force is applied in opposition to the tensioned coil 17, and the bolts 7 are tilted so that the heads 8, which press against the sheet of paper, are removed from the latter.

While I have described one embodiment of my invention, modifications thereof may be readily devised without departing from the spirit of my invention, and it is to be understood that such modifications come within the scope of the appended claims.

I claim:

1. A device of the type described comprising a bolt, a board having a conical-shaped opening for receiving said bolt, said bolt having a head bearing against one surface of the board, spring means for yieldingly holding said head in contact with the board, a pair of plates mounted on said bolt, one of said plates bearing against said board, a nut for holding

the second plate in position, said spring means being disposed between said plates, a spring connecting the second plate with said board, a handle movably carried by said board, and connections between said handle and said second plate.

2. A device of the type described comprising a board having a conical-shaped opening therein, the smaller diameter of said opening being disposed at the top of said board, a

member disposed in said opening of substantially the same diameter as the smaller diameter of said bore, said member having an enlarged head, the under surface of which is normally held in contact with said board, and means for moving said member for rocking said head into an angle with respect to said board for receiving paper therebetween. 15

CHARLES E. BARKER.
